POWDER CONTAINER

Joseph J. Vendel, Manhattan, Kans.

Application July 10, 1933, Serial No. 679,802

4 Claims. (Cl. 65—45)

This invention has for its object the provision of a simple and inexpensive device by the use of which a plurality of powdery materials may be carried in a single container and either material discharged at the will of the user.

The invention seeks to provide novel means for maintaining the two materials out of contact and for controlling the distribution or discharge of the materials.

10 The invention also seeks to provide a device for the stated purpose which will be very cheap and may be produced rapidly and which will be highly efficient for the purposes for which it is designed.

15 The invention is illustrated in the accompanying drawings and consists in certain novel features which will be hereinafter first fully described and then more particularly defined.

In the drawings:—

20 Figure 1 is a side elevation of one embodiment of the invention.

Figure 2 is a section on the line 2—2 of Figure 1.

Figure 3 is a section through a device embodying another form of the invention.

Figure 4 is a cross section on the line 4—4 of Figure 3.

Figure 5 is a cross section on the line 5—5 of Figure 3.

30 Figure 6 is a view showing the divider and the distributor separated and in perspective and approximately in their proper relative positions.

Figure 7 is a view showing another form of divider or separator in elevation with the container body in section.

Figure 8 is a section on the line 8—8 of Figure 7.

Figure 9 is a sectional view showing another form of container and a separator or divider adapted for the form of container shown.

Figure 10 is a sectional view taken at right angles to Figure 9, the line 9—9 in Figure 10 indicating the plane of the sections shown in Figure 9.

45 Figure 11 is a detail view of a further modification.

In carrying out the present invention, there is provided a cylindrical container 1 which may be of any preferred material and will generally be formed of stout cardboard or similar material in order to reduce the cost of production to the lowest possible stage. The body of the container may, however, be of other materials and in Figures 9 and 10 it is shown as formed

of glass, the body 2, the bottom 3 and the divider or partition 4 being one integral structure.

In the form shown in Figures 1 and 2, the lower end of the cylindrical body is closed by a cap 5 which is permanently secured on the body 60 so as to seal the lower end thereof and the upper end is normally open but is to be covered by a cap 6. A divider or separator 7 is disposed within the body on a diameter of the same and has its lower end resting against the bottom cap 65 5 and is to be sealed to said cap in any preferred manner in order to avoid commingling of the contents of the container or leakage from one compartment to the other compartment. The separator or divider 7 is longer than the body 70 70 so that it will project above the upper end of the body and near its upper end it is provided on its side edges with shoulders 8 which are adapted to rest upon the upper edge of the body, as clearly shown in Figure 2, whereby the partition or divider or separator will be firmly positioned in the body. The head 6 fits closely upon the upper end of the body and extends over the upper edge of the partition or divider and it is provided in its opposite sides with groups of 75 80 perforations, as shown at 9, to permit outflow of the contents of the separate compartments as may be desired. In order to prevent discharge of material when it is not desired and to prevent discharge of the improper material, a damper 85 10 is fitted upon the head, this damper being in the form of an annulus fitting closely about the head so as to turn thereon and provided with openings 11 adapted to register with the discharge openings in the head or to be turned 90 out of alignment therewith so that the discharge openings will be covered, as may be desired.

Upon referring to Figures 2 and 3, it will be noted that the damper fits between flanges 12 and 13 at the top and bottom respectively of the head so that it will be effectually held in place but may be easily turned when desired. The openings 11 may be so disposed that both discharge openings in the head may be covered or both may be opened or one may be covered while the other may be uncovered, thus making it possible to discharge the contents of the container according to the wishes of the user.

Guarding and distributing means are provided at the upper end of the separator or partition 7 105 and in the form shown in Figures 3, 4 and 5, the guard consists of a plate 14 adapted to rest on the upper edge of the body and having its central portion doubled upon itself to form a pair of upwardly converging walls 15 which are united 110

at their upper edges so as to extend over the upper edge of the partition or separator and bear against the underside of the head. Openings 16 are formed in the plate 14, adjacent the edges 5 thereof, as clearly shown in Figures 3 and 4, to permit outflow of substances which may be placed in the respective compartments of the container, the substances then finding their way to the discharge openings 9 of the head. To retard the 10 flow and distribute the same so that the discharged material will be sprinkled upon the surface or substance to which it is to be applied without waste, distributors 17 are provided on the upper side of the plate 14 and each distributor 15 consists of a plate bent along its longitudinal center to provide diverging wings, as clearly shown in Figure 4. These distributors are disposed upon the plate 14 so that the fold or bight of each distributor passes around and houses the 20 discharge opening 10 and the wings extend upwardly and inwardly therefrom towards the center walls 15 of the guard. Outlet openings 18 are formed at the lower end of each distributor in the bight thereof so that the outflowing material 25 will be directed toward the discharge openings of the head. The distributors may be formed of any suitable material and will generally be formed of sheet metal, being provided at the lower end of each wing with a tongue 19 adapted 30 to be inserted through a slit provided therefor in the plate 14 and then bent against the underside of the plate, as will be understood, whereby the distributor will be very firmly and cheaply held in place.

35 The device is intended primarily as a condiment holder and, therefore, the names "Salt" and "Pepper" will be generally displayed upon the opposite sides of the body of the container, as shown in Figure 1. The utility of the device 40 is not, however, confined to its use as a holder for salt and pepper as other substances may be placed therein. Various spices may be disposed within the compartments or different forms of powders for treating the skin, such as talcum 45 powder and boric acid, so that those substances or materials which are generally used together or in alternation may be found in a single container of convenient form. By constructing the container of cardboard or similar material it can 50 be produced at a trifling cost so that it may be used at factories or other sources of produce to package goods and a customer may be provided with desired commodities in a single package.

Ordinarily the partition or separator will be so 55 located as to divide the container into two equal compartments but it will frequently happen that it will be desired to place in the container substances which are used in conjunction with each other but in different quantities, and to meet this 60 condition the separator or partition may be formed as shown in Figures 7 and 8 in which the partition 20 has its upper portion arranged on a diameter of the head or top cap of the container and its lower portion is turned to one side, the 65 lower portion being beveled, as shown in Figure 7, to conform to the curvature of the body of the container. In Figures 7 and 8 I have also shown the head cap of the device as being in the form of a truncated cone, being tapered upwardly and 70 provided with discharge openings in its opposite sides. The guards and distributors in this form of the invention are the same as those previously described.

75 It sometimes happens that the head cap does not fit as accurately as desired to the upper end

of the partition, and to meet this condition a packing may be placed between the extremity of the partition and the top of the cap, as will be understood.

In Figures 10 and 11 the container is shown in 80 the form of a glass vessel with the upper edge of the partition or separator in the same diametrical plane as the edge of the body. In order that the interior of the head may be divided so as to effect positive and complete separation of the different contents of the container an extension or supplemental partition 21 is provided which has its lower edge slotted so as to provide a plurality of tongues 22 which are bent alternately in 85 opposite directions and are then engaged over the upper edge of the partition 4, as clearly shown in Figure 9. The guards and distributors are then fitted over the extension or supplemental partition and correspond in all respects to those 90 shown in Figures 1 to 5 and heretofore described.

In Figure 11, the head cap 23 is shown in the 95 form of a dome arcuate in all lines of cross section and the partition 24 has its upper end shaped to fit against the underside of the cap and is provided with a central notch, indicated at 25, to permit the passage of the intermediate portion of the guard 26. The guard is thus held against turning movement relative to the partition and has its edges engaged against the ends of the 100 notch 25, but otherwise it is similar in all respects to the first described guard.

Having described the invention, I claim:

1. A container comprising a body having an 110 open upper end, a head cap fitted on the upper end of the body, a partition within the body, a guard extending across the upper end of the body from the head cap to the partition and provided with outlet openings adjacent its edge, and distributors upon the guard within the head 115 cap and provided adjacent the guard with outlet openings.

2. A container comprising a body having an 120 open upper end, a partition in the body, a head cap fitted on the upper end of the body, a guard 125 extending across the upper end of the body from the head cap to the partition and provided with outlet openings adjacent its edge, and distributors secured upon the guard and having diverging wings extending towards the partition, said distributors having outlet openings in their bights adjacent their lower ends and the bights of the 130 distributors housing the outlet openings in the guard.

3. A container comprising a body having an 130 open upper end, a partition in the body, a head cap fitted on the upper end of the body and having discharge openings at opposite sides, a supplemental partition fitted on the upper end of the 135 partition and extending to the top of the head cap, a guard extending across the upper end of the body from the sides of the head cap to the upper edge of the supplemental partition, and distributors on said guard.

4. A container comprising a cylindrical body 140 having an open upper end, a head cap fitted on the body and having discharge openings in its opposite sides, a partition within the body extending from a diameter of the body at its upper end to the bottom of the body at one side thereof 145 and having a vertical portion disposed within the head cap, and a guard fitting across the upper end of the body and spanning the partition.
